DRAPERY HOOKS

Stanley A. Wilkie, % Wilkie Industries,
304 S. Mears Ave., Whitehall, Mich.

Filed Apr. 9, 1958, Ser. No. 727,496

1 Claim. (Cl. 24—86)

This invention relates generally to support means for suspending draperies on bars and hangers, and in particular is directed to a novel hook form for hanging draperies from conventional horizontal bars so that the head of the drape does not sag outwardly from the wall.

One difficulty observed in hanging draperies with conventional prior art drapery hooks is that the head or top of the drape tends to fall forwardly and to sag outwardly away from the vertical owing to the couple or turning moment exerted by the weight of the drape acting in a line horizontally offset from the center of support of the hook on the bar. The drapery hook of the present invention provides an improved suspension for a drape by the use of which the objectionable forward sag of the head of the drape is opposed by the action of a counter-balancing couple due to the weight of the hook and additional weights that may be added.

In prior art drapery hooks of which applicant is aware the fabric of the drape is stitched to head-shaping upright portions joined to hook portions which lie forwardly of the suspension hook, the displacement being in many instances greater than a half inch. The upper and lower ends of the prong support devices lie respectively above and below the hook hanger bar or rod, with the result that a turning moment is produced due to the weight of the drape depending from the lower end of the prong, causing it to rotate about the point of support on the bar so that the upper end overhangs away from the wall. The resulting sagging is displeasing, and often adversely affects the hanging and folds of the drape.

As a solution to the problem indicated above, it is an object of the present invention to provide a suspension hook device whose construction minimizes the tendency of drapery support prongs to be rotated out of the vertical.

It is a further object of the present invention to realize a counter-balancing drapery hook whereby a lighter weight drape is automatically counterbalanced by the weight of rearwardly extending portions of the hook, and heavier drapes deliberately may be counterbalanced by the addition of weights on a lever arm formed integrally with the hook.

According to the invention, a counter-balancing hook is constructed to provide a suitable vertical prong, pin, or array of uprights as drapery attaching elements, to whose lower end there is integrally joined a counter-balancing lever arm portion extending rearwardly and horizontally or substantially horizontally, with a return bend continuing in the same plane obliquely upward and bent twice to define a hook portion whose point of support lies close to the upright.

In carrying the invention into effect rigid material such as steel, brass or other suitable metal wire forms are shaped to provide vertical prongs or other drapery attachment portions, and a suspension hook portion either integral with or joined integrally with such portion is shaped like the figure "S" whose lower horizontal limb is formed as a lever arm straight portion extending from the base of the prong or other drapery attachment,

2

the bar-engaging portion of the hook being bent relatively sharply and disposed relatively close to the drape supporting portions.

The invention will be best understood from a consideration of the following detailed description taken in connection with the accompanying drawings setting forth preferred embodiments of the invention, such embodiments being presented as illustrative of the practice of the invention and not necessarily as limiting the construction to the precise forms described, which forms may be obviously modified within the scope of the appended claims.

In the drawings,

Fig. 1 is a side elevation view of a hook with drape fabric attached, showing the actions of the various forces acting on the hook;

Fig. 2 is a perspective sketch showing a hook associated with a supporting bar for a drape;

Figs. 3 and 4 are respectively side elevation and front elevation views of the hook of Fig. 2;

Fig. 5 illustrates a modified form of hook having multiple prong drape attaching portions; and,

Fig. 6 illustrates a hook having a pin type of drapery attachment.

Referring now more particularly to the drawings a drapery hook having a drape attachment portion 11 to which a drape generally indicated as D in Fig. 1 may be fastened in any suitable manner, has a hook portion 13 which rides upon a drapery bar or track 10. A lever arm horizontal portion designated 12 extends rearwardly away from the drape connected to the lower end of the upright portion 11, and connects with the hook-forming part by an obliquely disposed return straight portion 14 which completes a right-angle triangle with the sides 11 and 12. The opening of the hook is designated at 16, between the prong portion 15 which extends downwardly rearwardly generally in the same direction as the part 14, and the lower end of the part 14. It will be seen that the parts 15, 13, 14 form an inverted substantially U-shaped suspending hook with upper and lower downwardly extending arms, the lower arm 14 being fixed to the rear end of the lever arm 12. The base of the U forms the point of suspension 13 of the hook, such point being very close to an intermediate portion of the leg element 11.

The nature of the forces and couples exerted on the hooks when draperies are suspended on a track 10 may be appreciated by examination of Fig. 1. The weight of the drape and the mass of that portion of the hook lying forwardly of the bar 10 is represented by the downwardly directed arrow A. The combined weight of the rearwardly extending hook portions 12, 14, and 15, and any additional weighting device such as that indicated by 17, is represented by the downwardly directed arrow C. The upwardly directed arrow B through the point of support of the hook at 13 is indicated as the sum of the forces A and C.

The offset distance in a horizontal direction between the lines of action of the components A and B is preferably made as small as practical, and may in practice be realized as a distance of from $\frac{1}{4}$ to $\frac{3}{16}$ inches. The undesired couple which tends to cause forward droop of the head of the drape, has a magnitude which is the product of the force A multiplied by the offset distance referred to. The length of the horizontal arm portion 12 may be chosen in accordance with the particular application intended and should be made as large as practical and may conveniently extend for distances of from $1\frac{1}{4}$ inches to $1\frac{3}{4}$ inches horizontally from the fabric. It will be noted that the major portion of the length of the lever arm 12 as well as the lower and upper arms 14 and 15 of the hook lie to the rear of a vertical plane passing through

70

the point of suspension 13 of the hook and hence the weight of the major portion of the lever arm 12 and the arms 14 and 15, and the extension thereof rearwardly of the point of suspension, will tend to counterbalance the leg element and hold it perpendicular or substantially perpendicular.

The counterbalancing couple is equal to the product of the force B multiplied by the distance between a vertical passed through the point 13 and the location of the latter force. It is also preferable that the point of support 13 lie at a distance above the lever arm 12 which is chosen to be of the order of $\frac{2}{3}$ of the total height of the prongs 11. The counterbalancing weight 17 may take any suitable form and may be realized, for example, as a slotted lead slug which is compressed to grip the arm 12.

In supporting the lighter weight draperies no additional weight 17 need be provided where the number of hooks used is sufficient to properly shape the head of the drape. For example with hooks of the type indicated in Figs. 2, 3, and 4, spaced along the width of the drape at distances of the order of four inches on centers, hook supports formed of steel wire of 0.090 inch gauge with arms 12 measuring $1\frac{1}{4}$ inches long have provided satisfactory counterbalancing.

Where the depth of the hanger bar 10 in the vertical direction is relatively large, as in Fig. 2, the return portion 14 is bent back at a more acute angle. The width of the aperture 16 need be only large enough to admit the bar with its narrower end presented towards the opening.

Any suitable disposition of drapery support attachment elements 11 may be employed depending on the nature of the drapery head to be realized, and both plastic pointed forms such as are shown in Fig. 5 or pin forms as shown in Fig. 6 may have the counterbalancing portion attached thereto.

In fabricating the device of Figs. 2, 3, and 4 the prongs 11 may be formed as U-shaped loops to the base of which an integral bent wire portion comprising the elements 15, 14, and 12 is spot welded or brazed. Similarly the device of Fig. 5 may comprise a pair of U-shaped vertical loops

of different widths to which the lever arm 12 of the lower end of a hook is similarly welded or brazed.

From the foregoing it will be seen that the present invention provides a novel construction of a suspension device for attachment to the head of a drape and for hanging the drape on the horizontal bar, wherein the turning moments developed due to the offsetting of the vertical components of force are equalized about the point of support. Such hooks may be fabricated by simple methods and at relatively low cost, and may be adjusted precisely for drapery fabrics of any weight.

The embodiments of the invention in which an exclusive property or privilege is claimed are defined as follows:

A supporting hook for draperies comprising an upright substantially straight leg element adapted to be secured to a header portion of a drapery, an inverted generally U-shaped suspending hook at the rear of said leg element, the base of the U providing the point of suspension, said point of suspension being disposed very close to an intermediate portion of said leg element with the two arms of the U extending downwardly and rearwardly to dispose their major portions rearward of the point of suspension of the hook, and a substantially straight lever arm having one end fixed to the lower end of said leg element and its other end fixed to the end of the lower arm of said hook, said lever arm extending rearwardly from the leg element to dispose a major portion of its length rearwardly of a vertical plane passing through the point of suspension of the hook, whereby the weight of said rearwardly disposed major portion of said lever arm and hook and the extent thereof rearwardly of said point of suspension will tend to counter-balance the leg element and hold it substantially perpendicular.
